UNITED STATES PATENT OFFICE.

FRANK L. CROSS, OF MYSTIC, CONNECTICUT, ASSIGNOR TO CROSS PAPER FEEDER COMPANY, OF BOSTON, MASSACHUSETTS, A CORPORATION OF MAINE.

SHEET-FEEDING MACHINE.

No. 854,079.

Specification of Letters Patent.

Patented May 21, 1907.

Application filed July 31, 1905. Serial No. 271,904.

To all whom it may concern:

Be it known that I, FRANK L. CROSS, a citizen of the United States, and a resident of Mystic, Connecticut, county of New London, have invented certain new and useful Improvements in Sheet-Feeding Machines, of which the following is a specification.

The invention relates to machines for feeding sheets to printing presses or other machines, and more especially to the construction and arrangement of the frame for supporting and carrying the various parts of the feeding mechanism and to the devices for raising and lowering the supply table upon which the sheets are placed by the operator.

I have embodied the features of the invention in a feeding mechanism of that class known as "continuous feeders" in which a bank of feathered or fanned out sheets are piled upon a supply table and are transferred from this supply table to a feed board where the front end of the pile is acted upon by devices which separate and deliver the individual sheets. In this type of machine the separating and delivering devices are arranged below the supply table and it is frequently desirable to raise the supply table out of the way in order to give convenient access to the parts below the table. Certain features of the invention relate to devices for conveniently and quickly raising and lowering the supply table which is pivoted at its front end in the usual manner. The supply table is thus raised and lowered by means of one or more supporting arms pivoted below the supply table and having their supporting ends so connected with the supply table that they may be moved longitudinally along the table, thus swinging the arms about their pivots and either raising or lowering the table according as the arms are moved toward or away from a position at right angles to the table. When the table is at either limit of its movement, the arm or arms stand in an inclined position and stops are provided for limiting the movement of the arm or arms with relation to the table and thus maintaining the table in its adjusted position. The means which I prefer to employ for moving the supporting ends of the arms longitudinally of the table, consists of one or more pinions secured to a shaft carried in the sup-

porting arms and arranged to engage and travel along corresponding racks secured to the supply table.

Feeding mechanisms of the character above referred to are usually mounted and carried in a frame adapted to be applied to the usual feed board of a printing press and this frame is usually formed in sections so that the front section or sections may be folded and swung up out of the way when it is desired to use the feed board of the press for feeding sheets by hand. When the frame is thus folded for the purpose of using the feed board of the press, the front end of the rear section frame remains in position upon the feed board and as this portion of the frame frequently occupies a position at some distance forward of the rear end of the feed board, it prevents the proper arrangement of large sheets upon the feed board and thus reduces the capacity of the press. In order to overcome this objectionable feature of this class of feeding mechanism and at the same time enable the location of the feeding and separating devices at a convenient and most effective position with relation to the front end of the feed board during the use of the automatic feeding mechanism, I have provided devices for withdrawing the rear section of the frame and the front folded sections carried thereby to a position where the front end of the rear section rests upon the rear end of the feed board, thus enabling the feed board to receive the largest sheets in case the press is to be used with a hand feed.

The various features of the invention will be understood from the following detailed description of the mechanism in which I have embodied them and will be pointed out in the claims. This mechanism in which I have embodied the features of invention is shown in the accompanying drawings, in which

—Figure 1 is a side elevation showing so much of the supporting framework of a feeding mechanism as is necessary to a full understanding of the features of improvement; Fig. 2 is a sectional detail on line x—x Fig. 1; and Fig. 3 is a sectional detail on line y—y Fig. 1.

In the construction shown in the drawings A indicates the cylinder of a cylinder printing

press and B the usual feed board for the press upon which the sheets are placed when the machine is being fed by hand.

The various parts of the feeding mechanism for separating and feeding the sheets automatically to the press are carried and supported in a frame adapted to be applied to the feed board B. This frame as shown in the drawings consists of a rear section C, and 10 two front sections D E. The rear section of the frame is made up of side plates c c' connected by means of connecting bars c², the side plates on opposite sides of the frame being properly connected by cross rods in the usual manner. The side plates c' support the front end of the supply table F, the rear end of the feed table G, the feeding drum H, and the devices which coöperate with the drum in feeding the bank of sheets from the 15 upper supply table to the feed table G. These devices may be of the usual and well known construction and are not herein illustrated as they form no part of the present invention.

25 The side plates c of the rear section support the various devices and mechanisms for separating the sheets from the feathered bank on the feed table G and delivering the sheets from the bank. The details of these 30 mechanisms are not material to the present invention and are not herein illustrated.

The front sections D E of the frame are pivoted together at e and the section D is pivoted to the rear section C at d. These 35 sections are constructed to rest upon the feed board B and carry and support the various mechanisms and devices which coöperate with the separating and delivery devices in delivering the sheets against the front gages 40 of the press and in securing side register. When the use of the feeding mechanism is to be discontinued and the sheets fed to the press by hand, the section E is folded onto the section D and the section D swung up 45 about the pivot d and retained in its lifted position by means of hooks D' mounted on opposite sides of the supply table F and adapted to engage the pivot rod e of the frame sections.

50 The side plates c at the front of the rear section C rest upon the feed board B, while the rear end of the rear section is supported upon the rear support consisting of standards I arranged beneath the bars c² and connected with the press frame by brace rods I'.

In order that the frame of the feed mechanism may be withdrawn to the rear end of the feed board B when the sheets are to be fed to the press by hand, and thus enable the 60 proper positioning of large sheets upon the feed board, I have provided the bars c² with racks J arranged to engage pinions J' secured to a shaft J² which is journaled in the upper ends of the standards I forming the support 65 for the rear end of the rear section of the

frame. The shaft J² is also provided with collars J³ upon which the bars c² rest and over which they travel as the frame is withdrawn or advanced by the rotation of the shaft J². The shaft J² may be conveniently 70 rotated to withdraw or advance the rear section by means of a crank handle J⁴ attached to the end of the shaft J². By this mechanism the rear section and the folded front sections carried thereby may be readily and 75 conveniently withdrawn to give free access to substantially all of the feed board B when the feeding mechanism is out of use and may be readily returned to proper position with relation to the front gages of the printing 80 press when the feeding mechanism is to be used.

The supply table F is pivoted at f to the side plates c' in the usual manner so that it may be swung up when desired to give access 85 to the mechanism under the supply table.

When in normal position the supply table is supported by means of two arms K arranged at opposite sides of the supply table and pivoted at K' to the side plates c. The 90 upper ends of the arms K are connected by means of a shaft K² which is mounted in bearings in the upper ends of the arms. This shaft plays in slots K³ formed in plates K⁴ which are secured to the under side of the 95 supply table F. When the supply table is in its normal position the shoulder K⁵ formed by the rear end of the slot K³ engages the shaft K² and limits the movement of the arm K longitudinally of the table so that the table is firmly supported upon the pivoted 100 arms K.

When the table F is to be raised the shaft K² at the upper ends of the arms K is caused to travel along the slots K³ thus swinging the 105 arms K toward a position at right angles to the table F and consequently raising the table. When the arms K pass the position perpendicular to the table F the shaft K² engages the ends K⁶ of the slots K³ which then 110 form stops for limiting the movement of the arms K under the weight of the table so that the table is firmly supported in this position.

The means for causing the shaft K² to travel backward or forward along the slots 115 K³ consists of two racks K⁷ secured to the under side of the table F and two pinions K⁸ secured to the shaft K² and arranged to engage the racks. The shaft K² may be conveniently revolved to cause the pinions to 120 travel along the racks K⁷ by means of a crank arm K⁹ connected to the end of the shaft K².

While I prefer to employ two arms, two racks and coöoperating pinions, it will be understood that the number of arms, or the 125 number of racks and pinions may be varied as desired and as best suits the conditions under which the mechanism is to be used. The same is true with relation to the devices 130

for withdrawing and advancing the frame, and it will be further understood that various modifications and changes in the details of construction and arrangement may be made without departing from the essential features of the invention.

Without attempting to specifically describe the various forms and modifications of mechanism in which the features of invention may be embodied, what I desire to claim is:—

1. In a sheet feeding mechanism the combination with a pivoted supply table, of racks secured to the table, arms pivoted below the table, a shaft mounted in said arms, guideways on said table for said shaft, and pinions on the shaft engaging the racks.

2. A sheet feeding mechanism having in combination, a supporting frame provided with a rear section adapted to rest on the feed board of a press, one or more folding front sections, a rear support for the rear section, and devices for withdrawing and advancing the supporting frame.

3. A sheet feeding mechanism having in combination, a supporting frame provided with a rear section adapted to rest on the feed board of a press, one or more folding front sections connected with the rear section, a rear support for the rear section, a shaft mounted in the rear support, and connections between the shaft and rear section for withdrawing and advancing the frame by the rotation of the shaft.

4. In a sheet feeding mechanism the combination with a pivoted supply table, of an arm pivoted below the table, a rotatable pinion mounted in the arm, and a rack on the table engaged by the pinion.

5. In a sheet feeding mechanism the combination with a pivoted supply table, of racks secured to the table, arms pivoted below the

table, a shaft journaled in said arms, pinions on said shaft engaging said racks, and stops for determining the travel of the pinions. 45

6. In a sheet feeding machine the combination with a feed table of a supply table having its front end pivoted above the rear end of the feed table, one or more supporting arms pivoted below the supply table and 50 manually operated mechanism for swinging said arms to raise and lower the supply table.

7. In a sheet feeding mechanism the combination with a feed table of a supply table pivoted above the feed table, one or more 55 supporting arms pivoted below the supply table, and stops on the supply table for the arms arranged to lie on opposite sides of the vertical plane through the pivotal axis of the arms when engaged by the arms. 60

8. In a sheet feeding mechanism the combination with a feed table of a supply table pivoted above the feed table, one or more supporting arms pivoted below the supply table, and devices mounted on the supply table and upper end of the arms for moving the ends of the arms longitudinally along the table to raise and lower the same. 65

9. A sheet feeding mechanism having in combination, a supporting frame provided with a rear section adapted to rest on the feed board of a press, one or more folding front sections, a rear support for the rear section, a shaft mounted in said support, one or more racks on the rear section, and one or 70 more pinions on the shaft engaging said racks to withdraw and advance the frame by rotation of the shaft.

In witness whereof, I have hereunto set my hand, this 28th day of July 1905.

FRANK L. CROSS.

In the presence of:

IRA L. FISH,
KATHARINE A. DUGAN.
